UNITED STATES PATENT OFFICE.

FRANK. C. TROWBRIDGE, OF SYRACUSE, NEW YORK, ASSIGNOR OF ONE-HALF
TO MARTIN J. MARA, OF SAME PLACE.

CARPET-STRETCHER.

SPECIFICATION forming part of Letters Patent No. 419,979, dated January 21, 1890.

Application filed April 3, 1889. Serial No. 305,897. (No model.)

To all whom it may concern:

Be it known that I, FRANK. C. TROWBRIDGE, of Syracuse, in the county of Onondaga, in the State of New York, have invented new and useful Improvements in Carpet-Stretchers, of which the following, taken in connection with the accompanying drawings, is a full, clear, and exact description.

This invention relates to the class of carpet-stretchers in which a foot-board armed with teeth adapted to engage the carpet is operated by a lever coupled to the said board; and my invention consists in the improved construction and combination of parts, constituting a simple, inexpensive, and very convenient and most efficient carpet-stretching device, as hereinafter fully described and specifically claimed.

In the annexed drawings, Figure 1 is a perspective view of my improved carpet-stretcher. Fig. 2 is a side elevation of the same. Fig. 3 is an inverted plan view of the foot-board; and Fig. 4 is a transverse section on line xx , Fig. 3.

Similar letters of reference indicate corresponding parts.

A represents a wooden board. The front edge I protect by a metallic facing c. To the under side of said board I attach wire rods d d d, and preferably countersink them in the board so as not to unduly wear the carpet. The front ends of these wire rods project through the metallic facing c, and are thereby sustained laterally, while the rear ends thereof are bent at right angles and are inserted vertically in the board A, and are thus prevented from turning. To the central portions of the side edges of the board I attach eyebolts or screw-eyes t, on which I hang the wire bail b, the central portion of which is extended over the board A.

L represents a lever by which the stretcher is operated. Said lever is armed with a spike f at its lower end, so as to enable it to retain a secure hold in the floor during the operation of the carpet-stretcher, and a short distance above the lower end of the lever the hook h is attached to its side, on which hook the central portion of the bail is hung during the operation of the stretcher, said bail be-

ing readily detached from the hook when the carpet-stretcher is not in use.

e e denote two spurs, which are formed in one piece with a cross-bar e'. Said spurs are hinged closely to the rear face of the board A by means of staples l l, driven into the board and embracing the bar e' at its junctions with the spurs e e, as illustrated in Fig. 1 of the drawings.

The close hinged connection of the spurs e e to the rear of the board A, with the bail b connected to the central portions of the side edges of the board, is a very important feature of my invention, inasmuch as it allows the operator to adjust the spurs into their operative positions by merely a pressure of the operator's foot alternately on top of the front and rear portions of the board A, as herein-after explained.

My improved carpet-stretcher is operated as follows: The foot-board A is placed upon the portion of the carpet to be stretched. The lever L, connected to the bail b, is placed with its spike f on the floor in front of the board A, and with the upper end of the lever inclined rearward. Then by the pressure of the operator's foot upon the top of the front portion of the board and slightly pushing the top of the lever forward the board is tilted forward, which action is allowed by the connection of the bail b with the central portion of the side edge of the board and by the bail passing over the top of the front of the board. By tilting the board as aforesaid the front ends of the wire rods d d d are caused to engage the carpet. Then by pressing the upper end of the lever L farther forward the aforesaid board is drawn toward the foot of the lever, and thus the carpet is stretched. During the stretching operation the operator presses with his foot upon the board, so as to tilt it slightly rearward and thereby prevent the teeth or rods d d d from engaging the floor. During the said movement of the stretcher the spurs e e drag behind the board. Then after the carpet has been stretched, as aforesaid, the operator presses again on the front portion of the board, and thereby tilts said board, so as to raise the rear end thereof sufficiently to allow the spurs e e to stand.

erect. Then the operator by pressing his foot upon the rear portion of the board the aforesaid spurs are forced into the floor, and the board A is thus retained in its position.

5 Another salient feature of my invention is its simplicity of construction, the board A being easily formed of a plain piece of timber, the metallic facing being easily tacked onto the front thereof, the spurs e e being 10 easily bent from a piece of wire. The staples l l are readily driven into the board to hinge the spurs thereon. The screw-eyes t t are likewise easily applied to the side edges of the board, and the bail h is easily bent out 15 of a piece of wire and hooked onto the aforesaid screw-eyes.

My improved carpet-stretcher is also adapted to be folded in a neat and compact manner, inasmuch as the bail b is readily unhooked from the lever L.

20 Having thus described my invention, I claim—

As an article of manufacture, a carpet-

stretcher consisting of a foot-board A, a metallic facing c on the front of said foot-board, 25 the rods d d d, countersunk in the under side of said foot-board, and having their front ends projecting through the metallic facing and their rear ends bent at right angles and inserted vertically in the said board, the bail 30 b, hung on the central portions of the side edges of the board and extending over the front thereof, the lever L, connected to said bail, the spurs e e, formed in one piece with the cross-bar e', and the staples l l, attached 35 to the rear face of the board and embracing the bar e' at its junctions with the spurs e e and hinging the said spurs close to the board, substantially as set forth.

In testimony whereof I have hereunto signed 40 my name this 25th day of March, 1889.

FRANK. C. TROWBRIDGE. [L. S.]
